UNITED STATES PATENT OFFICE.

GEORGE M. GRAHAM, OF CHICAGO, ILLINOIS, ASSIGNOR TO G. A. EDWARD KOHLER, OF CHICAGO, ILLINOIS.

GIRDER FOR REINFORCED CONCRETE STRUCTURES.

No. 910,124.

Specification of Letters Patent,

Patented Jan. 10, 1900.

Application filed October 17, 1907. Serial No. 397,847.

To all whom it may concern:

Be it known that I, GEORGE M. GRAHAM, a citizen of the United States of America, and a resident of Chicago, in the county of 5 Cook and State of Illinois, have invented certain new and useful Improvements in Girders for Reinforced Concrete Structures, of which the following is a specification.

This invention relates to tubular trussed 10 girders for use in reinforced concrete structures in which the girders are wholly embedded in the mass of concrete which constitutes the main portion of the structure. And the present improvement has for its 15 object to provide a simple and efficient structural arrangement and combination of parts whereby a light, strong and economical truss girder is provided for such purposes, and which is adapted for ready and economical 20 assemblage of the parts in the skeleton supporting frame of a reinforced concrete building, all as will hereinafter more fully appear.

In the accompanying drawings:—Figure 25 1, is a side elevation illustrating the present girder in place in the skeleton reinforcing frame of a reinforced concrete building. Fig. 2 is a sectional plan of the same. Fig. 3 is an enlarged fragmentary side view. 30 Fig. 4 is a transverse section on line $\alpha-\alpha$, Fig. 3. Fig. 5 is an enlarged detail side view of an end fitting of the girder. Fig. 6 is a sectional plan view of the same partly on line $\alpha'-\alpha'$ and on line $\alpha''-\alpha''$ Fig. 5. Fig. 7 35 is an enlarged transverse section of the central part of the girder.

Similar numerals of reference indicate like parts in the several views.

Referring to the drawings, 1 represents 40 an outer vertical member, and 2 an outer horizontal member of the skeleton frame of a reinforced concrete building, such as set forth in my prior Letters Patent No. 865,490 of Sept. 10, 1907.

45 3 are fittings by which the aforesaid members are connected together and which also affords a support and connection for the upper and lower longitudinal members of the truss girder hereinafter described. Such fittings are of substantially the same construction as that set forth in my former patent No. 865,489 of Sept. 10, 1907; the novelty in the present construction comprising the provision of lateral brackets on opposite 50 sides of the fitting for the support and at-

attachment of the diagonal brace rods of the truss girder hereinafter described. Such runner brackets may be of any usual and suitable construction, but preferably comprise integrally formed studs 4 on the sides 60 of the fitting and separate runner brackets 5 recessed to fit over said studs, and secured in place by holding bolt 6 passing through central orifices in both studs and brackets, as shown more particularly in Fig. 6 of the 65 drawings.

7 and 8 are the upper and lower tubular longitudinal members of the truss girder, supported at their respective ends in open top sockets formed thereon on the fitting 3, 70 and having a spaced relation as shown in Figs. 1, 3, 4 and 7 of the drawings.

9 is a vertical post or strut arranged between the longitudinal members 7 and 8, midway their length, and provided with top 75 and bottom bearing shoes 9' and 9'' respectively, and which are preferably formed separate from the post 9 and provided with receiving sockets for the ends of said post as shown more particularly in Fig. 7. Such 80 arrangement is adapted to provide a substantial bearing contact between the parts and maintain the central portion of the longitudinal members in proper spaced relation.

10 are counterpart diagonal tension members, each comprising a pair of loop shaped members inclined in opposite directions and having their looped ends surrounding the aforesaid runner brackets 5 on the sides of the upper fitting 3 aforesaid, while their 90 middle portions engage the under side of a bracket or shoe arranged on the under side of the lower longitudinal truss member 8 midway the length of the same and preferably below the post 9 as shown.

95 11 is the bracket or shoe above referred to, and which in its preferred form as illustrated in Fig. 7, comprises the shoe or bracket 11 an intermediate thrust block 12 in loose bearing contact with the underside 100 of the truss member 8 and a series of adjusting screws 13, screwing through the shoe 11 and having bearing against the underside of the thrust block 12, the function of which is to move the shoe away from the thrust 105 block after the girder parts are assembled, to impose tension of the required stress upon the diagonal tension members 10 aforesaid.

14 and 15 are upper and lower longitudinal bearings or runner strips, having bear 110

ing on the upper surface of the upper longitudinal girder member 7 and on the lower surface of the lower longitudinal girder member 8 respectively, and formed with a series of runner lugs 16 and 17 projecting from their outer surfaces as shown. Such outer surfaces as well as said lugs have a rounded form so as to permit of the ready tensioning of the supplementary diagonal wire bracing now to be described.

18 and 19 are two series of diagonal bracings arranged in crossed relation and each formed of a single length of wire rove in a continuous manner around the upper and lower longitudinal girder members 7 and 8 and having bearing upon the runner strips 14 and 15 and around the runner lugs 16 and 17 thereof, and attached at the respective ends of the truss girder to the end portions thereof, or continued to form the diagonal bracing of an immediately adjacent girder which may be arranged in right angle relation to the one upon which the diagonal bracing is first applied.

20 is a sectional casing adapted to inclose the girder just described and constitutes a mold cavity for the reception of the mass of concrete which forms the main body of the present reinforced concrete girder of a building.

Having thus fully described my said invention what I claim as new and desire to secure by Letters Patent, is:—

1. A truss girder for reinforced concrete structures comprising upper and lower longitudinal truss members, an intermediate strut interposed between said members, lateral attaching brackets located at the ends of the upper longitudinal member, an intermediate shoe arranged beneath the lower longitudinal member, and a pair of diagonal tension members arranged at opposite sides of the girder and extending from the ends of the girder and beneath the shoe aforesaid, such tension members comprising looped rods the loops of which engage the lateral attaching brackets aforesaid.

2. A truss girder for reinforced concrete structures comprising upper and lower longitudinal truss members formed of round tubing, an intermediate strut interposed between said members, lateral attaching brackets located at the ends of the upper longitudinal member, an intermediate shoe arranged beneath the lower longitudinal member, and a pair of diagonal tension members arranged at opposite sides of the girder and extending from the ends of the girder and beneath the shoe aforesaid, such tension members comprising looped rods the loops of which engage the lateral attaching brackets aforesaid.

3. A truss girder for reinforced concrete structures comprising upper and lower longitudinal truss members, an intermediate

strut interposed between said members, lateral attaching brackets located at the ends of the upper longitudinal member, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, and means for adjusting the shoe to and from the lower longitudinal member.

4. A truss girder for reinforced concrete structures comprising upper and lower longitudinal truss members formed of round tubing, an intermediate strut interposed between said members, lateral attaching brackets located at the ends of the upper longitudinal member, an intermediate shoe arranged beneath the lower longitudinal member, a pair of diagonal tension members arranged at opposite sides of the girder and extending from the ends of the girder and beneath the shoe aforesaid, such tension member comprising looped rods the loops of which engage the lateral brackets aforesaid, and means for adjusting the shoe to and from the lower longitudinal member.

5. A truss girder for reinforced concrete structures comprising upper and lower longitudinal truss members formed of round tubing, an intermediate strut interposed between said members, lateral attaching brackets located at the ends of the upper longitudinal member, an intermediate shoe arranged beneath the lower longitudinal member, a pair of diagonal tension members, arranged at opposite sides of the girder and extending from the ends of the girder and beneath the shoe aforesaid, such tension members comprising looped rods the loops of which engage the lateral brackets aforesaid, and means for adjusting the shoe to and from the lower longitudinal member.

6. A truss girder for reinforced concrete structures comprising upper and lower longitudinal truss members, an intermediate strut interposed between said members, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

7. A truss girder for reinforced concrete structures comprising upper and lower longitudinal truss members, an intermediate strut interposed between said members,

upper and lower longitudinal bearing strips arranged on the top of the upper truss member and the bottom of the lower truss member and provided with runner lugs, and multiple bracings of wire wound in crossed relation around the longitudinal members and having bearings upon the runner strips and around the runner lugs.

8. A truss girder for reinforced concrete
16 structures comprising upper and lower longi-
tudinal truss members, an intermediate
strut interposed between said members, lateral
attaching brackets located at the ends
of the upper longitudinal member, an in-
13 termediate shoe arranged beneath the lower
longitudinal member, a pair of diagonal ten-
sion members arranged at opposite sides of
the girder and extending from the ends of
the girder and beneath the shoe aforesaid,
20 such tension members comprising looped
rods the loops of which engage the lateral
brackets aforesaid, upper and lower longi-
tudinal bearing strips arranged on the top
of the upper truss member and the bottom
25 of the lower truss member and provided
with runner lugs, and a diagonal bracing
of wire wound around the longitudinal
members and having bearing upon the run-
ner strips and around the runner lugs.

30 9. A truss girder for reinforced concrete
structures comprising upper and lower lon-
gitudinal truss members, an intermediate
strut interposed between said members, lat-
eral attaching brackets located at the ends
35 of the upper longitudinal member, an inter-
mediate shoe arranged beneath the lower
longitudinal member, a pair of diagonal
tension members arranged at opposite sides
of the girder and extending from the ends
40 of the girder and beneath the shoe aforesaid,
such tension members comprising looped
rods the loops of which engage the lateral
brackets aforesaid, upper and lower longi-
tudinal bearing strips arranged on the top
45 of the upper truss member and the bottom
of the lower truss member and provided
with runner lugs, and multiple bracings of
wire wound in crossed relation around the
longitudinal truss members and having bear-
50 ing upon the runner strips and around the
runner lugs.

10. A truss girder for reinforced concrete structures comprising upper and lower longitudinal truss members formed of round tubing, an intermediate strut interposed between said members, lateral attaching brackets located at the ends of the upper longitudinal member, an intermediate shoe arranged beneath the lower longitudinal member, a pair of diagonal tension members arranged at opposite sides of the girder and extending from the ends of the girder and beneath the shoe aforesaid, such tension member comprising looped rods the loops 55 of which engage the lateral brackets aforesaid.

70 said, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

11. A truss girder for reinforced concrete structures comprising upper and lower longitudinal truss members formed of round tubing, an intermediate strut interposed between said members, lateral attaching brackets located at the ends of the upper longitudinal member, an intermediate shoe 80 arranged beneath the lower longitudinal member, a pair of diagonal tension members arranged at opposite sides of the girder and extending from the ends of the girder and beneath the shoe aforesaid, such tension 85 member comprising looped rods the loops of which engage the lateral brackets aforesaid, upper and lower longitudinal bearing strips arranged on the top of the upper truss member and the bottom of the lower truss 90 member and provided with runner lugs, and multiple bracings of wire wound in crossed relation around the longitudinal truss members and having bearing upon the runner strips and around the runner lugs. 95

12. A truss girder for reinforced concrete structures comprising upper and lower longitudinal truss members, an intermediate strut interposed between said members, lateral attaching brackets located at the ends 100 of the upper longitudinal member, an intermediate shoe arranged beneath the lower longitudinal member, a pair of diagonal tension members arranged at opposite sides of the girder and extending from the ends 105 of the girder and beneath the shoe aforesaid, such tension members comprising looped rods the loops of which engage the lateral brackets aforesaid, means for adjusting the shoe to and from the lower longitudinal member, upper and lower longitudinal bearing strips arranged on the top 110 of the upper truss member and the bottom of the lower truss member and provided with runner lugs, and a diagonal bracing 115 of wire wound around the longitudinal members and having bearing upon the runner strips and around the runner lugs.

13. A truss girder for reinforced concrete structures comprising upper and lower longitudinal truss members formed of round tubing, an intermediate strut interposed between said members, lateral attaching brackets located at the ends of the upper longitudinal member, an intermediate shoe arranged beneath the lower longitudinal member, a pair of diagonal tension members arranged at opposite sides of the girder and extending from the ends of the girder and beneath the shoe aforesaid, such tension mem- 130

ber comprising looped rods the loops of which engage the lateral brackets aforesaid, means for adjusting the shoe to and from the lower longitudinal member, upper and lower longitudinal bearing strips arranged on the top of the upper truss member and the bottom of the lower truss member and provided with runner lugs; and a diagonal bracing of wire wound around the longitudinal members and having bearing upon the runner strips and around the runner lugs.

14. A truss girder for reinforced concrete structures comprising upper and lower longitudinal truss members, an intermediate strut interposed between said members, lateral attaching brackets located at the ends of the upper longitudinal member, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, means for adjusting the shoe to and from the lower longitudinal member, the same comprising a thrust plate and a series of adjusting screws screwing through the shoe and having bearing against the thrust plate, upper and lower longitudinal bearing strips arranged on the top of the upper truss member and the bottom of the lower truss member and provided with runner lugs; and a diagonal bracing of wire wound around the longitudinal members and having bearing upon the runner strips and around the runner lugs.

15. A truss girder for reinforced concrete structures comprising upper and lower longitudinal truss members formed of round tubing, an intermediate strut interposed between said members, lateral attaching brackets located at the ends of the upper longitudinal member, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, means for adjusting the shoe to and from the lower longitudinal member, the same comprising a thrust plate and a series of adjusting screws screwing through the shoe and having bearing against the thrust plate, upper and lower longitudinal bearing strips arranged on the top of the upper truss member and the bottom of the lower truss member and provided with runner lugs; and a diagonal bracing of wire wound around the longitudinal members and having bearing upon the runner strips and around the runner lugs.

16. A skeleton reinforcing frame for con-

crete buildings comprising vertical columns, fittings secured thereto and forming a support for a girder, a trussed girder comprising upper and lower longitudinal truss members, an intermediate strut interposed between said members, lateral attaching brackets on the sides of the aforesaid fittings, an intermediate shoe arranged beneath the lower longitudinal member, and a pair of diagonal tension members arranged at opposite sides of the girder and extending from the ends of the girder and beneath the shoe aforesaid, such tension members comprising looped rods the loops of which engage the lateral attaching brackets aforesaid.

17. A skeleton reinforcing frame for concrete buildings comprising vertical columns, fittings secured thereto and forming a support for a girder, a trussed girder comprising upper and lower longitudinal truss members formed of round tubing, lateral attaching brackets on the sides of the aforesaid fittings, an intermediate strut interposed between said members, an intermediate shoe arranged beneath the lower longitudinal member, and a pair of diagonal tension members arranged at opposite sides of the girder and extending from the ends of the girder and beneath the shoe aforesaid, such tension member comprising looped rods the loops of which engage the lateral attaching brackets aforesaid.

18. A skeleton reinforcing frame for concrete buildings comprising vertical columns, fittings secured thereto and forming a support for a girder, a trussed girder comprising upper and lower longitudinal truss members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, and means for adjusting the shoe to and from the lower longitudinal member.

19. A skeleton reinforcing frame for concrete buildings, comprising vertical columns, fittings secured thereto and forming a support for a girder, a trussed girder comprising upper and lower longitudinal truss members formed of round tubing, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension member comprising looped rods the

loops of which engage the lateral brackets aforesaid, and means for adjusting the shoe to and from the lower longitudinal member.

20. A skeleton reinforcing frame for concrete buildings comprising vertical columns, fittings secured thereto and forming a support for a girder, a trussed girder comprising upper and lower longitudinal truss members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, and means for adjusting the shoe to and from the lower longitudinal member, the same comprising a thrust plate and a series of adjusting screws screwing through the shoe and having bearing against the thrust plate.

21. A skeleton reinforcing frame for concrete buildings comprising vertical columns, fittings secured thereto and forming a support for a girder, a trussed girder comprising upper and lower longitudinal truss members formed of round tubing, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

22. A skeleton reinforcing frame for concrete buildings comprising vertical columns, fittings secured thereto and forming a support for a girder, a trussed girder comprising upper and lower longitudinal truss members, an intermediate strut interposed between said members, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

23. A skeleton reinforcing frame for concrete buildings comprising vertical columns, fittings secured thereto and forming a support for a girder, a trussed girder comprising upper and lower longitudinal truss

members, an intermediate strut interposed between said members, upper and lower longitudinal bearing strips arranged on the top of the upper truss member and the bottom of the lower truss member, and provided with runner lugs, and multiple bracings of wire wound in crossed relation around the longitudinal members and having bearing upon the runner strips and around the runner lugs.

24. A skeleton reinforcing frame for concrete buildings comprising vertical columns, fittings secured thereto and forming a support for a girder, a trussed girder comprising upper and lower longitudinal truss members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

25. A skeleton reinforcing frame for concrete buildings comprising vertical columns, fittings secured thereto and forming a support for a girder, a trussed girder comprising upper and lower longitudinal truss members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, upper and lower longitudinal bearing strips arranged on the top of the upper truss member and the bottom of the lower truss member and provided with runner lugs, and multiple diagonal bracings of wire wound around the longitudinal truss members and having bearing upon the runner strips and around the runner lugs.

26. A skeleton reinforcing frame for concrete buildings comprising vertical columns, fittings secured thereto and forming a support for a girder, a trussed girder comprising upper and lower longitudinal truss members formed of round tubing, lateral attaching brackets on the sides of the aforesaid fittings, an intermediate strut interposed between said members, an intermediate shoe

arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, upper and lower longitudinal bearing strips arranged on the top of the upper truss member and the bottom of the lower truss member and provided with runner lugs, and a diagonal bracing of wire wound around the longitudinal truss members and having bearing upon the runner strips and around the runner lugs.

27. A skeleton reinforcing frame for concrete buildings comprising vertical columns, fittings secured thereto and forming a support for a girder, a trussed girder comprising upper and lower longitudinal truss members formed of round tubing, lateral attaching brackets on the sides of the aforesaid fittings, an intermediate strut interposed between said members, an intermediate shoe arranged beneath the lower longitudinal member, a pair of diagonal tension members arranged at opposite sides of the girder and beneath the shoe aforesaid, such tension members comprising looped rods the loops of which engage the lateral brackets aforesaid, means for adjusting the shoe to and from the lower longitudinal member, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

28. A skeleton reinforcing frame for concrete buildings comprising vertical columns, fittings secured thereto and forming a support for a girder, a trussed girder comprising upper and lower longitudinal truss members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, upper and lower longitudinal bearing strips arranged on the top of the upper truss member and the bottom of the lower truss member and provided with runner lugs, and multiple diagonal bracings of wire wound around the longitudinal truss members and having bearing upon the runner strips and around the runner lugs.

29. A skeleton reinforcing frame for concrete buildings comprising vertical columns, fittings secured thereto and forming a support for a girder, a trussed girder comprising upper and lower longitudinal truss members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, means for adjusting the shoe to and from the lower longitudinal member, the same comprising a thrust plate and a series of adjusting screws screwing through the shoe and having bearing against the thrust plate, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

30. A skeleton reinforcing frame for concrete buildings comprising vertical columns, fittings secured thereto and forming a support for a girder, a trussed girder comprising upper and lower longitudinal members, lateral attaching brackets on the sides of the aforesaid fittings, an intermediate strut interposed between said members, an intermediate shoe arranged beneath the lower longitudinal member, a pair of diagonal tension members arranged at opposite sides of the girder and extending from the ends of the girder and beneath the shoe aforesaid, such tension members comprising looped rods the loops of which engage the lateral brackets aforesaid, means for adjusting the shoe to and from the lower longitudinal member, the same comprising a thrust plate and a series of adjusting screws screwing through the shoe and having bearing against the thrust plate, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

31. A skeleton reinforcing frame for concrete buildings comprising vertical columns, fittings secured thereto and forming a support for a girder, a trussed girder comprising upper and lower longitudinal truss members formed of round tubing, lateral attaching brackets on the sides of the aforesaid fittings, an intermediate strut interposed between said members, an intermediate shoe arranged beneath the lower longitudinal member, a pair of diagonal tension members arranged at opposite sides of the

girder and extending from the ends of the girder and beneath the shoe aforesaid, such tension members comprising looped rods the loops of which engage the lateral brackets aforesaid, means for adjusting the shoe to and from the lower longitudinal member, the same comprising a thrust plate and a series of adjusting screws screwing through the shoe and having bearing against the thrust plate, upper and lower longitudinal bearing strips arranged on the top of the upper truss member and the bottom of the lower truss member and provided with runner lugs, and a diagonal bracing of wire wound around the longitudinal members and having bearing upon the runner strips and around the runner lugs.

32. A skeleton reinforcing frame for concrete buildings comprising vertical columns, fittings secured thereto and forming a support for a girder, a trussed girder comprising upper and lower longitudinal truss mem-

bers, an intermediate strut interposed between said members, lateral attaching brackets on the sides of the fittings, the same comprising integral studs on the fittings separate runner brackets recessed to fit said studs and a bolt securing the brackets in place, an intermediate shoe arranged beneath the lower longitudinal member, and a pair of diagonal tension members arranged at opposite sides of the girder and extending from the ends of the girder and beneath the shoe aforesaid, such tension members comprising looped rods the loops of which engage the lateral attaching brackets aforesaid. 25 30 35
